UNITED STATES PATENT OFFICE.

CLARENCE WILLIAM ERNST VELLGUTH, OF SAN FRANCISCO, CALIFORNIA.

CARBURETER.

1,171,679.

Specification of Letters Patent. Patented Feb. 15, 1916.

Application filed October 3, 1911. Serial No. 652,566.

To all whom it may concern:

Be it known that I, CLARENCE W. E. VELLGUTH, a citizen of the United States, residing at San Francisco, in the county of San Francisco and State of California, have invented new and useful Improvements in Carbureters, of which the following is a specification.

This invention relates to carbureters, particularly those adapted to use on motor vehicles.

It has for an object to improve the mixture of air and hydrocarbon liquid fuel.

The most approved carbureter construction now involves the use of a jet in the path of the air passing to the engine, with means to produce a partial vacuum differing from the atmospheric pressure proportionately to the speed of the engine, whereby the fuel will be ejected from the jet in a quantity proportionate to the quantity of air passing. It is appreciated that this method results in directing the fuel through the passing air in a limited area and more or less unevenly—that is—all air passing the jet may not receive the same proportion of fuel. Also, the jet simply forms the fuel into a myriad of globules, most of which, owing to their small size are almost immediately evaporated and absorbed by the air. The globules, however are of irregular size, many are not thoroughly absorbed within a proper time, and by their weight tend toward certain bends or sides of the intake pipes through which the mixture is conducted to the engine. If it be a one cylinder engine the mixture will lack uniformity; if the engine have two or more cylinders, there will often be a difference in the quality of the mixture reaching the several cylinders. It has been noted that in some cases gasoline accumulated in the inlet pipe. Lack of uniformity of the mixture, or stratification, results in an irregular operation of the engine to which it is supplied, with loss of power and waste of fuel.

It is an object of this invention to provide a jet device the action of which will be modified to overcome some objections above noted, and to combine therewith means to obviate stratification of the mixture.

A further object of the invention is to present an improved float governor, operative with equal efficiency at any inclination of the carbureter in any direction.

Another object is to construct a throttle of improved form.

An important object of the invention is to enable the construction of a carbureter to occupy a very small space with a very large capacity for supplying gas.

It is also the purpose to allow the device to be easily taken apart and assembled. In this connection it is an important object to enable the removal of the fuel reservoir while the remaining parts remain in operative position, so that it may be readily determined whether the float and connected parts are freely and properly operative. Also, to make possible the removal of either the fuel control elements or the air regulating devices without disconnection of the outlet and throttle from the feed duct to the engine.

Other objects and advantages will be apparent from the following description, and from the drawings, in which—

Figure 1 is a vertical sectional view of the carbureter in inoperative position, Fig. 2 is a vertical section of the body castings at right angles to Fig. 1, Fig. 3 is a horizontal sectional view taken adjacent the upper side of the fuel chamber, looking downward, Fig. 4 is a similar view in the intake chamber, Fig. 5 is a similar view in the mixing chamber, a portion of the upper diffusion screen being broken away, Fig. 6 is a horizontal sectional view centrally of the throttle outlet, indicated by the line 6—6 in Fig. 1.

There is illustrated a mixing chamber somewhat in the form of a cupola, and surmounting the entire device, having the upwardly directed outlet opening or port 11 with suitable means for effecting the usual connection with the intake ducts of automobile engines and the like. However, by arranging the outlet upwardly, the necessity for one turn in the passage to the engine cylinder is obviated, for it is necessary to locate the carbureter below the cylinder of the engine to be out of the way of operations necessary in the tending of the engine. The cupola is circular in horizontal section, and has in threaded engagement therewith the circular floor plate 12, serving to close off the mixing chamber from the air intake chamber 13 therebelow. This latter chamber is formed by a casting 14 having a circular open top portion receiving snugly a suitable boss 15 on

the plate 12 and having an outstanding flange 16 secured to a similar flange 16' on the cupola by suitable screws as shown.

The intake casting 14 is provided with a circular seat boss 17 upon which is set the upper edge portion of a fuel bowl 18, the joint thus formed being properly ground to be liquid tight. The intake casting is provided with a floor portion 19 forming a cover for the fuel bowl, and centrally of this floor a downwardly projecting stem 20 is formed, projected slidably through a suitable opening in the bottom of the bowl, being slightly tenoned and having threads outwardly of the bowl upon which is engaged a suitable nut 21, holding the bowl securely to the casting 14 and making a tight fit at the bottom of the bowl to prevent escape of fuel. The stem 20 is provided with an enlarged recess 22, extending a considerable distance within the bowl, and from its lower portion a reduced passage 23 opens through the lower end of the stem having threaded therein the needle valve 24 whereby it is closed, the valve being retained in adjusted position by a suitable nut 24'. Opening into the bowl adjacent its bottom and communicating with the passage 23 intermediately of the reduced part of the needle valve there are small ducts 25. The stem 20 at its junction with the floor 19 is provided with an exteriorly threaded enlargement or boss 26, having a horizontal peripheral groove 27 therearound from which three small passages 28 extend through the lower side of the boss adjacent the periphery of the stem 20. The groove 27 is closed by means of a collar 29 threaded on the boss and removable for cleaning of the groove. Leading in to the groove 27 from a point above the seat 17, there is a fuel duct 30, at the outer end of which there is a suitable threaded boss 31 for making connection to a fuel supply. Engaged on the stem beneath the boss 26, there is a collar 32 having apertured ears 33 disposed beneath each of the passages 28, and vertically slidably in these passages are small valves 34 arranged to be moved upwardly to close the passages. Loosely slidable on the stem beneath the collar 32 there is a vertically movable collar 35, upon which are mounted the gimbals 36 and 37 of usual form, the inner being pivoted diametrically on the ring collar 35, while the outer one 37 is pivoted on the inner gimbal on an axis perpendicular to the axis of movement of the inner gimbal. The outer gimbal is in the form of a right angle in cross section, having an outwardly projecting flange 38 upon which is set an annular cork float 39, adapted, by this mounting, to maintain a constantly level position upon the surface of the liquid admitted to the bowl. The collar 35 is provided with sev-

eral vertical slots 35' in which there are slidable small pins 20' to check downward movement of the collar beyond a proper point. It will be noted that the stems of the valves 24 project downwardly below the ears 33 so as to be engaged by the collar 35 when moved upwardly by the float. As the valves 34 are triangularly spaced, it will be appreciated that they will each be firmly pressed upward to seat in the openings of the passages 28 whereby the entrance of fuel will be checked. Opening into the upper part of the enlarged recess 22 there are vent passages 40 for the free escape of air under access of fuel to the bowl.

Slidably in the recess 22 there is a hollow auxiliary air valve stem 41, having the enlarged lower portion 42 engaged snugly within and against the sides of the recess, the reciprocal movement of which is limited by the seat collar 43 threaded in the upper end of the recess and engaging closely against the stem. The passages 40 open through this collar, and in the stem there is an encircling recess 44 extending longitudinally of the stem a sufficient distance to maintain the passages 40 in communication with the air chamber 12 after the stem has been raised a short distance. A short helical spring 45 is secured to the collar 43 to the upper end of which there is secured a valve element A held thereby snugly seated in an enlarged circular air port 46, for movement upwardly therefrom against the action of the spring. The valve element comprises a lower collar 47 threaded on the stem 41 and having the spring secured thereto, and an upper head portion 48 also threaded on the stem 41 the two having a suitable cushion material 49 coengaged therebetween and shaped to bear directly upon the valve seat surface formed around the air port. The stem 41 is slotted as at 41' below the valve A for access of air thereto as will be explained.

A sleeve 50 is secured in the lower part of the valve stem stopping short adjacent the lower part of the slots 41', and snugly fitted in this sleeve there is a fuel duct pipe 51, projecting below the stem and engaging snugly and slidably in the upper part of the reduced passage 23 in the stationary stem 20. Its upper end projects above the member 48 of the valve A and has threaded thereon the nozzle disk 52, spaced above which is the nozzle head 53 secured to the disk 52 in a suitable manner. The member 48 of the valve A has an upstanding neck 54 surmounted by the laterally projected circumscribing lip collar 55 curved slightly downward toward its outer edge thus producing a convex spherical upper surface. The periphery of the nozzle disk 52 lies within that of the lip 55, and the periphery of the head 53 coincides with that of the lip, 130

the diameter of the latter and of the head being approximately the same. The opposed surfaces of the disk and head are also spherical and converge toward the surface 5 of the lip.

It will be noted that the plate 12 has a sleeve portion 56 in which there are a series of vertical slots 57, and slidably in these slots there are the extremities of quadrilateral arms of a spider 58 secured upon the upwardly projected stem 59 forming a portion of the head 53. This stem is tenoned, and threaded and the spider is secured thereon by a nut and lock nut as at 60. The 10 spider includes an annular portion 61 abutting snugly against the sleeve portion 56, and secured thereto and completely covering the spider there is a screen 62, preferably of copper wire of about 30 meshes to the 15 inch, which may be overlaid by a heavier wire screen of coarser mesh, as shown, to support the lighter one. The annular portion of the spider 58 is apertured at suitable points and set in the apertures are the extremities of the arms of a spider 64 carried 20 on the stem 41 and confined between the lip collar 55 and the upper member 48 of the valve A. These arms are bowed downwardly, and carry therebeneath a screen 65, 25 similar to the one 62. The screen 62 is bowed upwardly. It will be seen that the construction of the head 53 and lip 55 form an annular nozzle B, directed toward the lower screen, and adapted to project fuel 30 laterally on all sides in the path of air entering through the port 46.

A throttle device is located at the upper part of the cupola and consists of a circular semi-spherical stationary member 66, having a supporting flange 67 secured by means of screws to a suitable shoulder 68 formed around the passage 11, as shown, its convex portion being disposed inwardly toward the nozzle B. Two sector-shaped openings 45 69 are formed at opposite sides of the web, each comprising about one third the total area of the web, and pivoted centrally thereof there are two somewhat similar devices acting as gates one above the other, the 50 lower, 70, having no flange part corresponding to that 67 on the base web, but lying revolvably within the passage 11, and adapted to lie in registry with the web 66 at times. One edge 71 is arranged to strike an inwardly projecting lug 72 formed on the base web frame centrally of one of the sector openings, to check movement of the gate 70 when it has moved far enough from over the web to cover half of each opening. The upper gate 73 is similar to the lower in plan with the exception that an extension 74 projects from one edge and a concentric slot 75 is formed in the adjacent gate portion, extending into the extension, and receiving 55 slidably therein a pin 76 carried by the gate

70, whereby upon movement of the upper gate beyond a certain distance, the lower one will be moved thereby, for complete closure of the outlet, as will be readily understood. The upper gate is provided with an upwardly presented rack portion 77, extending over a little more than one half its circumference, although it may be continued completely therearound if desired. For operating the gate this rack portion is engaged by the gear 78 carried by the shaft 79 revolvble in the wall of the outlet 11 and projecting outwardly thereof, where it carries a second gear 80. This latter gear is engaged by a rack sector 81 carried by a throttle lever 82, pivoted upon the side of the cupola below the shaft 79. This lever may be operated by the usual connections from the steering post levers of automobiles, and it should be noted that the device should be set initially with the gear 80 at one end of the sector 81. Certain types of automobile throttle control are arranged to operate to open the throttle by a movement of the lever in a certain direction, while other controls are intended to move the lever in an opposite direction. It will be seen that the present lever may be readily set for use with either form of control. One arrangement is illustrated, and if the opposite operation is desired, the gear 78 is moved to the opposite end of the shaft 79 and the sector 81 set initially with its opposite end adjacent the gear 80. Thus the same movement of the gates will result from an opposite movement of the lever 82.

It will be seen that by rotation of the plate 12, when the gasoline feed is disconnected, the entire operative portion of the carburetor excepting the throttle may be removed, and the several parts thereof disassembled for inspection and repair. Should it be desired only to inspect the mechanism in the float chamber within the fuel bowl, it is only necessary to cut off the gasoline supply without disconnecting the feed pipes, and remove the nut 21, when the bowl itself may be quickly detached, leaving the float and mechanism connected therewith exposed to view.

In use, the device being properly connected to the intake of an engine, it will be seen that a suction stroke will produce a rapid inrush of air through the slots 41 and through the nozzle. At the same time a quantity of fuel will be drawn through the duct 51, and directed downwardly upon the film of air passing over the lip 55. The space below the disk 52 for the passage of air is preferably larger than the space thereabove for the passage of gasoline, but may be arranged at such width as found most desirable. The movement of the air past the fuel passage will facilitate the raising of the fuel, and it will be appreciated that 130

the air will move much more rapidly than the fuel in its outward passage. The outgoing body of fuel will thus be rapidly disintegrated or torn apart by the body of air, 5 the action being somewhat in the nature of the wearing away of the fuel body by the air. Thus, instead of the fuel being diffused only by the peculiar form of the nozzle and the formation of a vacuum outside thereof, which permits the formation 10 of irregular sized globules, some of which are too large, the fuel is shredded and compressed by the air film, which moves so much more rapidly that the fuel particles 15 are torn apart before they have opportunity to form into too large units. Also, by the compression of the fuel by the air (which occurs against the lower face of the head 53), the absorption of the fuel by the air 20 is accelerated and its diffusion facilitated.

When the suction is sufficient to overcome the resistance of the spring 45, it will cause the lifting of the valve A, admitting a large body of air to the mixing chamber.

Should it happen that heavy particles of fuel are discharged from the nozzle, they will strike the screen 65, upon which they will become diffused and from which they will be lifted by the air admitted through 25 the port 46 by the valve A. At high speeds the air rushes through the screen 65 at a considerable speed, and should any particles of fuel of too large a size be carried upward before engaging the screen, or be 30 lifted therefrom, they will be dispersed by engagement with the second screen 62 above the nozzle.

After leaving the second screen, the fuel may be supposed to have been entirely absorbed, and as a further means to overcome 40 stratification, the throttle gates are so arranged as to cause such eddies in the gas as will make it sufficiently homogeneous.

By making the gates in the form of sphere 45 segments, they are adapted to resist the pressure of the outgoing gas thereagainst efficiently even though made of thin sheet material, and also the openings having a given peripheral extent will admit a larger 50 quantity of gas than if they were made in plane form.

What is claimed:

1. In a device of the class described, a mixing chamber, a nozzle, fuel connections 55 therefor, air connections for the nozzle, a circumscribing cage around the nozzle dividing the mixing chamber an air inlet in the chamber at one side of the cage, and an outlet opposite the inlet, said nozzle being 60 adapted to direct air and fuel toward the side of the cage adjacent the air inlet.

2. A device of the class described comprising a cupola part having an outlet opening and throttle means, a floor member carried by the cupola and having an enlarged 65 air port therein, a valve yieldingly seated in the port, an air chamber member therebeneath having a downwardly extending tubular stem, and a bowl centrally apertured and engaged around the stem with its 70 peripheral edge against the air chamber member, fuel supply and governing means for the bowl, the interior of said stem having communication with the interior of the bowl, a tubular member slidable in the stem 75 and having a reduced portion a spaced distance within the stem, a collar threaded in the upper portion of the stem and engaged in said reduced portion to limit movement of the tubular member, said tubular member being engaged through said valve, having lateral communication with the air chamber and being closed at its lower end, a duct member extending through the lower end of the tubular member and above its upper 80 end, a stationary valve element in the bowl aligned with the duct member, a nozzle device carried at the upper end of the tubular member for mixture and ejection of air and fuel passing through the tubular member. 90

3. In a device of the class described, a mixing chamber, an air space therebeneath, a tubular member projecting into the chamber from the air space, and forming communication therebetween, a fuel duct in the 95 tubular member, fuel connections therefor, a peripheral lip carried by the tubular member at its end within the mixing chamber, a collar on the duct having a surface adjacent the lip converging theretoward and 100 stopping short of its outer edge, a head member thereover and in spaced relation with the collar and forming an annular passage converging toward the lip, a screen member circumscribing and extending laterally from the tubular member beneath the lip and abutting the walls of the mixing chamber at the periphery of the screen, the opposed surfaces of said lip and head being inclined toward the intermediate portion of 110 said screen, an auxiliary air inlet beneath and within the boundary of the screen, and outlet means oppositely thereof in the mixing chamber.

In testimony whereof I have hereunto set 115 my hand in presence of two subscribing witnesses.
